UNITED STATES PATENT OFFICE.

WASYL T. LAPUK, OF GOODEVE, SASKATCHEWAN, CANADA.

BOMB.

1,147,177.

Specification of Letters Patent. Patented July 20, 1915.

Application filed April 2, 1915. Serial No. 18,717.

To all whom it may concern:

Be it known that I, WASYL T. LAPUK, a subject of the Emperor of Austria-Hungary, residing at Goodeve, in the Province 5 of Saskatchewan, Canada, have invented certain new and useful Improvements in Bombs, of which the following is a specification.

This invention relates to certain new and 10 useful improvements in bombs.

An object of the invention is to provide a bomb in the form of a spherical member including spherical elements and means operated exteriorly of the bomb for causing 15 the same to explode.

A further object of the invention is to provide a bomb including a centrally-disposed explosive member with radial cartridges containing shrapnel or other forms 20 of cartridges with spring-controlled means positioned exteriorly of the bomb whereby when the same contacts an object, the centrally-disposed explosive will cause the radial cartridges to be fired.

25 A still further object of the invention is to provide a bomb in which the outer surface is substantially completely covered with spring-controlled means adapted to cause the same to explode and to project the substance discharged therefrom in all directions.

With the above general objects in view and others that will appear as the nature of the invention is better understood, the same 35 consists in the novel construction, combination and arrangement of parts to be hereinafter more fully described and then claimed.

In the accompanying drawings which 40 show the preferred embodiment of the present invention and to which reference is had herein by like characters designating corresponding parts throughout the several views, Figure 1 is a plan view of the bomb. Fig. 2 is a cross-sectional view of the same. Fig. 3 is a detached perspective view of one 45 of the firing members. Fig. 4 is a cross-sectional view of one of the radially-disposed cartridges. Fig. 5 is a similar view 50 showing a cartridge of modified construction, and, Fig. 6 is a detached perspective view of the disk forming either the spacing member or inclosure for the radial cartridges.

55 Briefly described, the present invention includes concentrically-disposed spherical

members, one within the other, with an explosive substance carried by the central member and having radiating therefrom cartridges that are adapted to be fired or 60 exploded when the central firing substance is ignited, and to cause the cartridges to be exploded, I have provided spring-controlled firing pins passing through the concentric spherical members and carrying contact 65 disks at their outer ends adapted to force the pins inwardly into engagement with the centrally-disposed explosive substance.

Referring more in detail to the accompanying drawings, the reference numerals 70 10, 11 and 12 designate concentrically-disposed spherical members, one within the other and being equi-distantly spaced, with a detonative explosive substance 13, adapted to completely fill the inner spherical 75 member 10.

A plurality of cartridge members 14 radiate in every direction from the central spherical member 10 and these cartridges pass through the middle spherical member 80 11, as clearly shown in Fig. 2, with the outer ends thereof disposed inwardly of the outer spherical member 12. Each cartridge is divided into inner and outer compartments by the disk members 15, the inner compartment containing powder or other explosive designated 16 while the outer compartment 85 is filled with shrapnel or other bullets 17. A closure disk 15 is arranged in the outer end of each of the radial cartridges 14 to 90 hold the shot within the shell.

The mechanism for exploding the gun cotton contained in the inner member 10 includes firing pins 18 provided on their inner ends with spear points 19 and carrying 95 on their outer ends disks 20. Alined openings are provided in the spherical members 11 and 12 to provide for the passage of the pins 18 and a coil spring 21 surrounds these pins and is disposed between the members 100 11 and 12, the inner end of the spring engaging the member 11 while the outer end of the spring engages a collar 22 carried by the pin, and these springs are adapted to hold the firing members in their outermost position as shown in Fig. 2, so that the disks carried by the outer ends of the pins 18 substantially completely inclose the outer spherical member 12.

Fig. 5 shows a modification of the cartridge 14 and discloses another manner of 110 charging the same with powder and shot,

the interior of the shell 14 being divided into substantially four equal compartments, two of the opposite compartments adapted to contain explosive powder 16 while the other two compartments contain the shot 17.

It is to be noted that the inner spherical member 10 should be constructed of some thin material that may be easily pierced by the spear points 19 of the firing pins 18, so that when the bomb comes into contact with an object, the outwardly-disposed disks 20 are moved inwardly against the tension of the springs and the spear points 19 pierce the inner member 10 and engage the gun cotton 13 to explode the same. This explosion fires the cap 23 of each of the radial cartridges 14 and the powder 16 within the cartridge explodes and projects shot 17 through the outer member 12 in all directions.

While I have shown and described the preferred embodiment of my invention, I do not wish to confine myself to the exact details of construction shown, as various forms, modifications and arrangement of the parts as shown may be had without departing from the spirit and scope of the invention as claimed.

What I claim as new is:—

30 1. A device of the class described comprising a plurality of concentrically-disposed spherical members, a detonative explosive substance carried by the inner member, radial cartridges carried by the inner member and extending through the middle member, with the outer ends terminating short of the outer member, and means carried by the two outer members exteriorly operated and adapted to cause the centrally-

disposed substance to explode and fire the cartridges.

2. A device of the class described comprising concentrically-disposed spherical members, an explosive substance carried by the inner member, radial cartridges associated therewith, firing means including radially-disposed pins, operating disks for the pins carried by the outer ends thereof, and resilient means for holding the pins in a normal outward position, the last-mentioned means further serving to hold the outer spherical members in resilient spaced relation.

3. In a device of the class described, an inner chamber, an outer chamber, an explosive within the inner chamber, radially-disposed cartridges carried by the inner chamber and having their outer ends disposed within the outer chamber, firing members each including a pin section, a spear point carried by one end thereof, a disk carried by the outer end of each pin, a spring engaging said pin and associated with said casing adapted to hold the pin normally projected outward, said pin adapted to be moved inwardly to cause the spear point thereof to engage and pierce the inner receptacle to explode the contents thereof and subsequently explode the radial cartridges, said springs further serving to hold the walls of the outer chamber in resilient spaced relation.

In testimony whereof I affix my signature in presence of two witnesses.

WASYL T. LAPUK.
